UNITED STATES PATENT OFFICE.

OLIVER JEROME HELVEY, OF LA CRESCENTA, CALIFORNIA.

DESIGN FOR A STREET-LIGHTING LANTERN.

Application filed May 22, 1928. Serial No. 26,803. Term of patent 14 years.

To all whom it may concern:

Be it known that I, OLIVER JEROME HELVEY, a citizen of the United States, residing at La Crescenta, in the county of Los Angeles and State of California, have invented a new, original, and ornamental Design for a Street-Lighting Lantern, of which the following is a specification, reference being had to the accompanying drawing, forming a part thereof.

Figure 1 is a side elevation of a street lighting lantern showing my new design.

Fig. 2 is a transverse sectional view taken on line II—II, Fig. 1 looking in the direction of the arrows.

I claim:

The ornamental design for a street lighting lantern, as shown.

Signed at Los Angeles, in the county of Los Angeles, and State of California, this 10th day of May, 1928.

OLIVER JEROME HELVEY.
